UNITED STATES PATENT OFFICE.

JAMES GIBB STEWART, OF DUNDEE, SCOTLAND.

MEANS FOR PRODUCING MAGNIFICATIONS OF MINUTE MOVEMENTS.

1,392,239.

Specification of Letters Patent. Patented Sept. 27, 1921.

Application filed April, 2, 1920. Serial No. 370,840.

To all whom it may concern:

Be it known that I, JAMES GIBB STEWART, a subject of the King of Great Britain and Ireland, residing at 31 Isles Lane, Dundee, 5 Scotland, have invented new and useful Improvements in or Connected with Means for Producing Magnifications of Minute Movements, of which the following is a specification.

10 This invention, which relates to means for producing magnifications of minute movements particularly applicable for use in the construction of gaging, indicating, recording and like instruments, comprises the pro- 15 vision of two flexible members, each narrow in comparison with its length and thin ac- cording to the flexibility required, which is mainly angular flexibility about a longi- tudinal axis. These members are arranged 20 opposite one another with their longitudi- nal axes contained in a plane normal or ap- proximately so to their surfaces. At a po- sition, say, midway between their ends, the 25 members are rigidly connected together, and the ends of one member are fixed to a sta- 30 tionary support and those of the other to a movable frame, the arrangement being such that upon applying force to the movable frame in a direction at right angles to the 35 plane in which the longitudinal axes of the members are normally contained, angular movement is produced at the position where the members are connected about or approxi- 40 mately about a longitudinal axis contained in the aforesaid plane parallel, coincident or approximately so with the longitudinal axis of the member fixed to the stationary sup- port. The angular movement thus pro- 45 duced, which is proportional to the move- ment imparted to the movable frame, may be transmitted, indicated or recorded di- rectly, or provision may be made for the multiplication thereof.

The flexible members may be composed of 45 spring steel or other similar or suitable ma- terial and at the position of connection be arranged in surface contact or separated.

Some examples of construction according 50 to this invention will now be described with reference to the accompanying drawing, in which:—

Figures 1 and 2 are perspective views illustrating two constructions. Fig. 3 is a plan illustrating a modification.

55 In the drawing A and B designate two

flexible members composed of spring steel, C a stationary support to which the ends of the member A are fixed and D a movable frame to which the ends of the member B are fixed. At a position midway between 60 their ends the members A, B, are fixed together by a connector, in this case comprising an intervening distance piece E associated with two outside pieces E¹ E² secured together by screws E³. By these means the 65 movable frame D derives support partly from the stationary support C, supple- 70 mentary support and guidance being pro- vided, for example, in the case of Fig. 1 by straps F, F, fixed at one end one to each end of an extension D¹ of the frame D and at the other end to stationary standards G which form a lateral guide for the movable frame. The straps F, F, which may be composed of 75 spring steel or other suitable material, op- erate to guide the frame D when moved in a direction at right angles or approximately so to the plane containing the longitudinal axes of the members when in their normal condition, and the length of the straps F 80 may be such that the support C and frame D are separated by a distance which is equal to or greater or less than that at which nor- 85 mal support by the connected members A, B alone would produce, with the result that the members are deformed each from its origi- 90 nal, in this case straight, condition. The adjacent ends of the members A, B may thus be held at a greater or less distance apart than the adjacent portions at the position of connection.

A further example of means for supple- 95 menting the support and for so guiding the movable frame D that it is capable of being moved only in a direction at right angles or approximately so to the plane containing the longitudinal axes of the flexible mem- bers A, B when in their normal condition, 100 is embodied in the construction illustrated at Fig. 2, which construction corresponds in other respects with Fig. 1. In this case the lateral guide is formed by the extension D¹ of the movable frame D being arranged to extend through and slide in a fixed guide G¹. 105

The movement to be measured may, for example, be determined by applying the movement at the position H, see Figs. 1 and 2, derived, for instance, from a rod, sup- 110 ported with its free end placed in contact

with this place, the elongation of which under heating effects is desired to be measured. The elongation produced will thus operate to move the frame D and thereby produce an 5 angular movement of the connector E, the extent of which may be indicated directly by an index finger K extending from the connector E associated with a scale L over which the outer end of the finger moves.

10 A convenient method of multiplying the scale indication is shown at Fig. 3, in which case the part E¹ of the connector is furnished with an arm E⁴ having at its outer end a toothed segment N which meshes with 15 a toothed wheel P fixed upon a spindle P¹ on which is fixed an index finger K¹ arranged to move over a scale L graduated as required.

Other methods of supplementing the support and guiding the movable frame D may 20 be adopted, and although flexible members which in their natural condition are flat are particularly suitable, that condition is not essential. Further, the conditions at the position where the two members are connected, 25 in so far as the extent of angular movement produced is concerned, depend upon the distance which at this position the longitudinal axes of the two members are apart.

20 I claim:

1. An instrument consisting of two flexible members each narrow in comparison with its length and thin according to the flexibility required, arranged opposite one 35 another with their longitudinal axes contained in a plane normal or approximately so to their surfaces, a connector by which the two flexible members are rigidly connected together at a position between their 40 ends, a stationary support to which the ends of one member are fixed, a movable frame to which the ends of the other member are fixed, a lateral guide for the movable frame, and means to which the angular movements 45 of the connector are imparted, for the purposes set forth.

2. An instrument consisting of two flexible members each narrow in comparison with its length and thin according to the 50 flexibility required, arranged opposite one

another with their longitudinal axes contained in a plane normal or approximately so to their surfaces, a connector by which the two flexible members are rigidly connected together at a position between their 55 ends, a stationary support to which the ends of one member are fixed, a movable frame to which the ends of the other member are fixed, an extension from the movable frame, stationary standards, flexible straps fixed at 60 one end one to each end of the extension from the movable frame and at the other end to the stationary standards, and means to which the angular movements of the connector are imparted, for the purposes set 65 forth.

3. An instrument consisting of two flexible members each narrow in comparison with its length and thin according to the flexibility required, arranged opposite one 70 another with their longitudinal axes contained in a plane normal or approximately so to their surfaces, a connector by which the two flexible members are rigidly connected together at a position between their 75 ends, a stationary support to which the ends of one member are fixed, a movable frame to which the ends of the other member are fixed, a lateral guide for the movable frame, and an index finger to which the angular 80 movements of the connector are imparted, for the purposes set forth.

4. An instrument consisting of two flexible members each narrow in comparison with its length and thin according to the 85 flexibility required, arranged opposite one another with their longitudinal axes contained in a plane normal or approximately so to their surfaces, a connector by which the two flexible members are rigidly connected together at a position between their 90 ends, a stationary support to which the ends of one member are fixed, a movable frame to which the ends of the other member are fixed, a lateral guide for the movable frame, 95 and an index finger fixed to and extending from the connector, for the purposes set forth.

JAMES GIBB STEWART.
